UNITED STATES PATENT OFFICE

HERBERT L. CHAPIN, OF SWAMPSOOTT, MASSACHUSETTS, ASSIGNOR TO UNITED SHOE MACHINERY CORPORATION, OF PATERSON, NEW JERSEY, A CORPORATION OF NEW JERSEY

LIP TURNING MACHINE

Application filed March 16, 1931. Serial No. 522,983.

This invention relates to improvements in lip turning or channel opening machines and is herein illustrated as embodied in a lip turning machine having a rotary lip turning tool.

One object of the present invention is to improve the construction and mode of operation of lip turning tools of the rotary type to facilitate efficiency of operation and insure uniformity of results irrespective of variations in the character of the material acted upon as well as to eliminate the danger of burnishing or glazing the surface of the lip in such a way as to interfere with the cementing of the lip after the sole has been

stitched to the upper of the shoe.

With this object in view, a feature of the invention consists in the provision, in a machine of the class described, of a rotary lip turning tool comprising a member constructed and arranged to engage the lip of a channeled sole held against and fed past the tool and to exert wiping pressure upon the lip in directions lengthwise of the lip and flatwise

of the sole to open the channel and turn the lip over toward the face of the sole and to exert edgewise pressure yieldingly to form a shoulder at the base of the lip. As herein illustrated, a plurality of lip-engaging members are pivotally mounted upon a rotary carrier or hub, the arrangement being such that the members are urged outwardly by the action of centrifugal force as the hub rotates and are capable of yielding inwardly as the work is pressed against them. Each of the illustrated pivotally mounted members is provided with a lip-engaging surface, a portion of which is shaped and arranged to enter the channel in a sole and to turn the lip

of the channel by wiping over the face of the lip, and a portion of which is shaped and arranged to strike a light blow against the base of the lip in a direction substantially perpendicular to the edge of the sole and thereafter to wipe along the lip with a yielding rubbing action adapted to form a well-defined shoulder at the base of the lip without danger of burnishing the lip.

The invention further consists in features of construction and combinations and ar-

rangements of parts hereinafter described and claimed.

The invention will be explained with reference to the accompanying drawings, in which.

Fig. 1 is a side elevational view of a portion of a lip turning or channel opening machine having my improved lip turning tool applied thereto;

Fig. 2 is a side elevational view of the tool shown in Fig. 1, illustrating its mode of operation upon the sole of a shoe;

Fig. 3 is a bottom plan view of the tool, partially broken away;

Fig. 4 is a vertical sectional view taken along the line IV—IV of Fig. 3;

Fig. 5 is a sectional view taken along the line V—V of Fig. 2 but showing the lip turning blades in their inner or non-expanded positions;

Figs. 6 and 7 are elevational views of one of the lip turning blades constituting the lip turning tool, showing the blade as it appears from two different points of view;

Fig. 8 is a perspective view showing the tool in operation upon the outsole of a shoe;

Fig. 9 is a sectional view similar to Fig. 3 but illustrating the tool as it appears when in operation upon a piece of work;

Fig. 10 is a view, partially in vertical section and partially in side elevation, of a tool of modified construction, showing the tool in operative relation to a piece of work;

Fig. 11 is a perspective view of a shoe illustrating the appearance of the channel lip after it has been operated upon by the improved lip turning tool; and

Fig. 12 is a diagrammatic view illustrating certain characteristics in the mode of operation of the tool.

In Fig. 1 of the drawings, a rotary lip turning tool is shown as being applied to a lip turning or channel opening machine of a type commonly employed to open the channel and lay back the channel lip or flap of the outsole of a shoe after the outsole has been rough-rounded and channeled in the usual way. The lip turning tool, which is shown at 12 in the drawings, is fixedly secured upon the lower end of a spindle 14 which is jour-

naled in vertical bearings 16 formed in a frame or head 18. A pulley 20 secured to the spindle 14 between the bearings 16 is adapted to receive a belt 22 for driving the 5 spindle.

The lip turning tool 12 comprises a cylindrical carrier or hub 24 and three elongated lip turning members or blades 26 which are pivotally mounted on the hub 24 with 10 provision for a limited amount of outward swinging movement under the action of centrifugal force while the spindle 14 is being rotated. As shown, a bore 28 is formed in the upper portion of the hub 24 for receiving 15 the spindle 14 while the lower portion of the hub is reduced in diameter where the lip turning blades are located and is counterbored and tapped to receive a screw 30, the head 32 of which assists in holding the blades 26 in 20 place on the hub and functions in gaging the position of the work relatively to the blades as will hereinafter appear.

The illustrated blades 26 are shaped, as best shown in Fig. 5, to facilitate the compact 25 arrangement of the blades around the reduced lower portion of the hub 24, each blade having an outer lateral face 34 which is convex lengthwise of the blade, and a longitudinally concave inner lateral face 36 curved to 30 correspond to the curvature of the reduced lower portion of the hub 24. As shown, each lip turning blade 26 has a flat upper face 38 (Figs. 5, 6 and 7) adapted to engage an annular shoulder 40 on the hub 24 which 35 forms a thrust bearing for the blades and a pivot stud 42 projects upwardly from each blade, the stud being formed integrally with the blade at one end of the latter. The blades are assembled, as shown in Fig. 5, in spaced 40 relation around the reduced lower extremity of the hub 24 with the pivot studs 42 received and adapted to turn in vertical bores 44 in the upper portion of the hub. The pivot studs 42 are retained in the bores 44 by the 45 screw head or gage member 32, the margin of which supports the blades 26 by engagement with arcuate ribs 46 which are formed on the blades to assist in the lip turning operation as will be explained. The inner 50 faces of the blades 26 are relieved at 48 (see Fig. 5) to permit the blades to move outwardly about their pivots 42 under the action of centrifugal force as the tool is being rotated. To limit the outward movement of the lip 55 turning blades about their pivot studs there is associated with each blade a stop screw 50 which extends vertically through the upper portion of the hub 24.

Each stop screw 50 is formed with a conical 60 lower extremity 52 adapted to project into a complementary recess 54 in the respective lip turning blade and to engage a portion of the wall of the recess which constitutes a stop shoulder to cooperate with the stop screw. 65 By turning the screws 50 associated with the

several lip turning blades, thus raising or lowering the conical lower extremities of the screws with respect to the recess 54, the limit of outward movement of the blades may be varied and consequently the extent to which 70 the blades are permitted to yield inwardly as the work is pressed against them is correspondingly varied. As shown, lock nuts 56 may be provided on the screws 50 for securing 75 the screws in adjusted position.

To enable the blades 26 to perform the desired lip turning operation, each blade is further provided with a curved lower face 58 for engaging the under side of the lip, as best shown in Figs. 2, 6 and 8. This face 58 of each lip turning blade slopes downwardly lengthwise of the blade from the pivoted end of the blade (which is the portion which first comes into engagement with the lip as the tool rotates in the direction of the arrow in Fig. 8) toward the rear portion of the blade, the angle of slope becoming progressively less abrupt until the face 58 merges with a substantially horizontal surface 60 at the rear extremity of the blade. In a direction cross-wise of the blade the slope of the face 58 becomes progressively less abrupt from front to rear of the blade and at its inner extremity the face 58 blends gradually with the substantially vertical outer face of the rib 46. It will thus be seen that the curvature of the lip-engaging surface of each blade 26 is similar to that at one side of the bow of a boat. In the operation of the tool, the lip-engaging faces 58 of the blades 26 function to raise the lip to an upright position and gradually to turn it backwardly and downwardly toward the face of the sole, while the substantially horizontal surfaces 60 function to set the lip in its backwardly turned position, which position is illustrated in Fig. 2. The outer surfaces of the ribs 46 cooperate with the periphery of the screw head or gage member 32 to define an upright shoulder at the base of the lip. As shown in Fig. 2, the periphery of the gage member 32 acts upon that portion of the base of the lip which is below the upper surface of the sole, while the faces of the ribs 46 act upon that portion of the base of the lip which is above the upper face of the sole. The member 32, by engagement with the unyielding lowermost portion of the lip, functions effectively to gage the position of the lip with respect to the lip turning blades. The slight bevel of the periphery of the member 32, and the fact that the latter presents an unyielding surface to the material at the base of the lip, tends to prevent that member from riding out of the channel. The fact that the blades 26 are capable of yielding inwardly after coming into engagement with the lip enables each blade to remain in contact with the lip for a longer interval of time, and to have a greater area of contact 125 with the lip at each rotation of the tool 130

than if the blades were unyieldingly mounted. Thus, the blades are enabled to exert a yielding rubbing or wiping action upon the lip which is not only more effective for 5 the purpose of turning and setting the lip but also has practically no tendency to glaze or burnish the surface of the lip. The interval of time during which each blade remains in rubbing contact with the lip at each 10 rotation of the tool being dependent upon the amount which the blade is permitted to yield inwardly, that interval may be varied by adjusting the extent of movement of the blades by means of the screw 50.

15 In Fig. 10 there is shown a lip turning tool of modified construction wherein provision is made for gaging the location of the work relatively to the tool from the inwardly yielding blades themselves instead of from 20 a non-yielding member such as the screw head or gage member 32 hereinbefore described. As shown in Fig. 10, the lip turning blades which are indicated at 260 and which are pivotally mounted upon the carrier or hub 240 in the same manner as that already described is provided with ribs 460 which project downwardly to the lowermost extremity of the tool for engagement with that portion at the base of the lip which lies below the 25 upper surface of the sole. As shown, also, the heightwise curvature of the outer or lip-engaging surfaces of the rib 460 is such as to provide a slightly undercut surface for 30 engagement with the base of the lip, such a construction causing the ribbed lower portions of the blades to have a tendency to prevent the ribs from accidentally being forced out of the channel and the tool being 35 displaced from the desired operative relation with the lip of the sole. In this modified construction the lip turning blades are supported and held in their proper positions with respect to the hub 240 by means of an 40 annular flange 462 on a screw 300 which is 45 threaded into the tapped lower portion of the spindle-receiving bore 288 in the hub 240.

In presenting a shoe to the machine, the operator manually raises the channel lip at the end of the channel where the lip turning 50 operation is to begin and engages the root of the channel with the periphery of the gage member 32. As the tool 12 rotates, the curved work-engaging surfaces of the blades 26 wipe across the face of the channel lip, 55 raising the lip to an upright position and turning it backward toward the face of the sole, and applying an unyielding pressure tending to set the lip in its backwardly turned position. The outer face of each rib 60 46 strikes a light blow against the material at the base of the lip and thereafter exerts a yielding wiping pressure which results in defining a shoulder at the base of the lip without, however, exerting any tendency to 65 glaze or burnish that portion of the lip.

The mode of operation of the tool upon the work is clearly illustrated in the drawings, wherein a lasted shoe is indicated at A, the outsole of the shoe at B, the channel at C, and the channel lip or flap at D. As indicated by the arrows in Fig. 8, the tool 24 is rotated in a clockwise direction (viewed from above) and the work is drawn past the tool in the general direction of movement of the lip turning blades where the latter engage 70 the work. Thus, the rotation of the tool facilitates the feeding of the work. The periphery of the gage member 32 provides an unyielding abutment for engagement with the material at the bottom of the channel in 75 the sole. Because of the pivoted mounting of the lip turning blades the latter are swung outwardly and thus the lip engaging portions of the tool are radially expanded while the tool is rotating, with the result that the 80 lip engaging surfaces yield inwardly as the work is pressed against them. This yielding of the lip engaging surfaces results in reducing to a minimum any vibration imparted by the tool to the work and thus 85 makes it easier for the operator to handle the work to prevent the tool from riding out of the channel. Moreover, because of the yielding 90 of the lip turning blades the normal circular path of movement of the blades is 95 modified as the work is pressed against the blades.

Because of the modification of the path of movement of the lip turning blades a particularly advantageous result is accomplished with regard to the action of the tool upon the relatively thick and tough base portion of the lip of the sole. The action of the tool upon this portion of the lip will be 100 explained with special reference to Figs. 3, 6 and 12. As hereinbefore set forth, it is the rib portion 46 of the lip turning blade 26 which operates upon the base of the lip of the sole. The portion of the rib 46 which engages the lip is the portion located between 105 the points H and I in Figs. 3 and 6, that portion comprising a surface which is concentric with the axis of the tool when the lip turning blade occupies its inner or non-expanded position. The lip turning blade 26, however, occupies its outer or expanded position when it first engages the work at a 110 point corresponding approximately to the point H. The blade 26 then moves inwardly under the pressure of the work and finally 115 leaves the work approximately at the point I. The paths of the point H (which may be referred to as the striking point) and of the point I (which may be referred to as the 120 leaving point) are indicated diagrammatically by the dotted lines J and K, respectively, in Fig. 12. In that figure, the edge of a sole which is being operated upon is indicated at L, the base of the channel lip at M, and the edge of the lip, after the lip has been 125 130

turned, at N. As shown, the path J is circular until the striking point H on the lip turning blade contacts with the base of the lip at the point designated O in Fig. 12. 5 The point H then travels in a straight path to the point P during which time the lip turning blade yieldingly engages the work. The concentric portion of the curved face of the rib 46 which lies between the points H 10 and I then wipes across the base of the lip of the sole, after which the leaving point I travels through a straight path from P to Q in yielding engagement with the work. The lip turning blade is thus maintained in 15 yielding wiping engagement with the base of the lip for a substantial portion of each rotation of the tool and is made effective to turn the lip in such a manner as entirely to uncover the stitch-receiving groove M, and to 20 produce a well-defined shoulder at the base of the lip, and thus to insure against any interference by the lip with the stitching operation which is subsequently to be performed upon the sole. Because of the fact 25 that the lip turning blade engages the work yieldingly, however, it has no tendency to glaze or burnish the lip in such a way as to interfere with effective cementing of the lip after the sole has been stitched to the shoe 30 and the lip has been laid to close the channel and conceal the stitches.

Having described my invention, what I claim as new and desire to secure by Letters Patent of the United States is:

35 1. In a lip turning machine, a rotary lip turning tool comprising a member constructed and arranged to engage the lip of a channeled sole held against and fed past the tool and to exert wiping pressure upon 40 the lip in directions lengthwise of the lip and flatwise of the sole to open the channel and turn the lip over toward the face of the sole and to exert edgewise pressure yieldingly to form a shoulder at the base of the 45 lip.

2. In a lip turning machine, a rotary lip turning tool comprising a member constructed and arranged to engage the lip of a channeled sole held against and fed past 50 the tool and to exert wiping pressure upon the lip in directions lengthwise of the lip and both flatwise and edgewise of the sole to open the channel and turn the lip over toward the face of the sole and to form a shoulder at the base of the lip, said member being mounted to yield edgewise of the sole as said tool rotates.

60 3. In a lip turning machine, a rotary lip turning tool comprising a member constructed and arranged to engage the lip of a channeled sole held against and fed past the tool and to exert wiping pressure upon the lip in directions lengthwise of the lip and both flatwise and edgewise of the sole to open 65 the channel and turn the lip over toward the

face of the sole and to form a shoulder at the base of the lip, said member being supported against yielding movement flatwise of the sole but being mounted to yield edgewise of the sole as said tool rotates. 70

4. In a lip turning machine, a rotary lip turning tool comprising a member constructed and arranged to wipe across the lip of a sole in directions lengthwise of the lip and flatwise of the sole to press the lip toward the face of the sole and to apply yielding pressure to the base of the lip in a direction substantially perpendicular to the edge of the sole. 75

5. In a lip turning machine, a rotary lip turning tool comprising a carrier, and a member on said carrier constructed and arranged to strike a blow against the lip of a sole to form an upstanding shoulder at the base of the lip, and to exert wiping pressure upon the face of the lip in directions both flatwise and edgewise of the sole to turn the lip toward the face of the sole. 80

6. In a lip turning machine, a lip turning tool comprising a member mounted to revolve about an axis substantially perpendicular to the face of a lipped sole being operated upon and having a surface shaped and arranged to strike a blow at the base of the lip at each rotation of the tool. 85

7. In a lip turning machine, a lip turning tool comprising a member mounted to revolve about an axis substantially perpendicular to the face of a lipped sole being operated upon and constructed and arranged to wipe across the body portion of the lip and to strike a blow at the base of the lip at each rotation of the tool. 90

8. In a lip turning machine, a lip turning tool comprising a member mounted to revolve about an axis substantially perpendicular to the face of a lipped sole being operated upon to strike a blow at the base of the lip and thereafter to wipe yieldingly along the base of the lip in a direction lengthwise of the lip at each rotation of the tool. 95

9. A rotary lip turning tool having a lip engaging member constructed and arranged to exert wiping pressure in two directions substantially perpendicular to each other, the tool being mounted so that the pressure in one direction is unyielding and the pressure in the other direction is yielding. 100

10. A lip turning tool comprising a hub, a lip turning blade mounted on the hub and arranged to be held outwardly by centrifugal force and to yield inwardly while the hub is rotating, said blade having a lip engaging surface shaped to raise the lip of a channel in a sole to turn the lip over toward the face of the sole and simultaneously to rub yieldingly along the base of the lip. 115

11. A rotary lip turning tool comprising a hub, a plurality of lip turning blades pivotally mounted on the hub and arranged to 120

swing outwardly under the influence of centrifugal force about axes substantially perpendicular to the face of a sole being operated upon by the tool, and means for limiting the outward movement of said members.

12. A lip turning tool comprising a hub, a lip turning blade pivotally mounted on the hub and arranged with its pivotal axis substantially parallel to the axis of the hub, said blade having a lip engaging surface shaped to raise the lip of a sole and to turn the lip over toward the face of the sole and simultaneously to rub yieldingly along the base of the lip.

13. A lip turning tool comprising a rotary carrier, a lip turning member mounted on said carrier and adapted to move outwardly under the action of centrifugal force as said carrier rotates, a stop screw on said carrier for engaging said member to limit outward movement of the member to an extent variable in accordance with the adjustment of said screw, and means for locking the stop screw in adjusted position.

14. A lip turning tool comprising a hub, a lip turning blade pivoted for swinging movement about an axis parallel to the axis of rotation of the hub and having a recess in one side of the blade, and a screw carried by the hub and having a conical extremity arranged to project into said recess in said blade to limit the outward movement of the blade about its pivotal axis to an extent variable in accordance with the adjustment of the screw.

15. A rotary lip turning tool comprising a hub having a reduced portion, a plurality of lip turning members surrounding the periphery of said reduced portion, each of said members having a pivot stud received in a bore in the main portion of the hub and arranged to permit outward movement of said members under the influence of centrifugal force as said tool rotates, and means for retaining said members in assembled relation with said hub.

16. In a lip turning machine, a rotary lip turning tool comprising a member constructed and arranged to raise the lip of a sole and to wipe along the base of the lip in a direction lengthwise of the lip, said member being mounted to yield to extend the area of contact of said member with the base of the lip at each rotation of said tool.

17. In a lip turning machine, a rotary lip turning tool comprising a member constructed and arranged to raise the lip of a sole and to wipe along the base of the lip in a direction lengthwise of the lip, said member being mounted to yield to extend the area of contact of said member with the base of the lip at each rotation of said tool, and unyielding means engageable with the base of the lip for gaging the position of the work relatively to said member.

18. In a lip turning machine, means constructed and arranged to raise a lip of a sole and to wipe across the lip flatwise of the sole to turn the lip backward toward the face of the sole, and yieldable wiping means for forming a shoulder at the base of the turned lip.

19. A lip turning tool comprising a member adapted to rotate about an axis substantially perpendicular to the face of a sole, and a wiper member carried by said rotary member and movable under the influence of centrifugal force, said wiper member having surfaces shaped and relatively arranged for exerting wiping pressure against the lip of the sole in directions both flatwise and edgewise of the sole.

20. In a lip turning machine, a rotary carrier, a lip turning member on said carrier shaped and arranged to enter a channel in a sole and to engage the base of the channel lip to position the lip relatively to the tool, and a plurality of lip turning blades pivoted for swinging movements about axes parallel to the axis of rotation of said carrier, and having lip engaging surfaces shaped and arranged to raise the channel lip and turn it backwardly toward the face of the sole, and means for rotating said carrier.

21. A rotary lip turning tool comprising a hub having a reduced portion, a plurality of lip turning members surrounding the periphery of said reduced portion, each of said members having a pivot stud received in a bore in the main portion of the hub and arranged to permit outward movement of said members under the influence of centrifugal force as said tool rotates, and means fixed to said hub and engageable with said members for holding the latter in place, said means having a circular periphery engageable with the base of the lip to gage the position of the work relatively to said tool.

22. In a lip turning machine, a driven shaft, a hub on said shaft, a plurality of lip turning members mounted on said hub and adapted to be held normally in an outer position by the action of centrifugal force while said shaft is rotating and to yield inwardly to the pressure of the work, and a disk fixed to said hub and arranged to have peripheral engagement with the material at the root of the channel to gage the position of said members relatively to the work.

23. In a lip turning machine, a driven shaft, a hub on said shaft, a plurality of lip turning members mounted on said hub and adapted to be held normally in an outer position by the action of centrifugal force while said shaft is rotating and to yield inwardly to the pressure of the work, and a disk fixed to said hub and arranged to have peripheral engagement with the material at the root of the channel to gage the position of said members relatively to the work, said disk having

a beveled periphery tending to prevent the disk from riding out of the channel.

24. A rotary lip turning tool comprising a hub, a plurality of lip turning blades pivotally mounted on the hub and constructed and arranged to be held in an outer position under the action of centrifugal force while the tool is rotating and to yield to the pressure of the work, and a non-yielding gage arranged to engage the base of the lip of a sole to position the lip relatively to said blades.

In testimony whereof I have signed my name to this specification.
